UNITED STATES PATENT OFFICE

WILHELM FRIEDRICH HOHULIN, OF OTTAWA, ILLINOIS

FLUID REVERSING VALVE

Application filed March 4, 1930. Serial No. 433,104.

This invention relates to new and useful improvements in fluid reversing valves and more particularly to devices of this character which are especially adapted for use in association with cylinders having fluid actuated pistons therein but it is to be understood that a valve constructed in accordance with this invention is to be utilized for any purpose for which the same is found adapted.

10. The primary object of this invention is to provide, in a manner as hereinafter set forth, a fluid reversing valve of the aforementioned character which is adapted to function in a manner to reverse the flow of the fluid to a cylinder or other machinery with a very slight movement of the actuating means on the valve.

20. Other objects of the invention are to provide a valve of the character set forth which will be simple in construction, strong, durable, efficient in its use, and which may be manufactured at low cost.

All of the foregoing and still further objects and advantages of the invention may 25 become apparent from a study of the following specification, taken in connection with the accompanying drawings, wherein like characters of reference designate corresponding parts throughout the several views, and 30 wherein:—

Figure 1 is a view in front elevation of a valve constructed in accordance with this invention.

Figure 2 is a vertical longitudinal sectional view therethrough.

Figure 3 is a vertical transverse sectional view through the valve.

Figure 4 is a detail view in front elevation of the valve core removed from the casing.

40. Referring to the drawings in detail, it will be seen that the valve comprises a metallic casing 1 formed to provide a centrally disposed, substantially circular chamber 2 having an internally threaded integral outlet

45. boss 3 on its lower side in communication with said chamber. On its upper side, the casing 1 is provided with oppositely extending horizontally disposed internally threaded ports 4 and 5 to which suitable pipe connections (not shown) are coupled and extend

to a cylinder which also is not shown. The ports 4 and 5 communicate with the chamber 2 on opposite sides of a vertical partition 6.

The rear side of the casing 1 is open and a closure plate 7 is removably secured thereon through the medium of the screws 8. The closure 7 is provided with a centrally disposed threaded opening 9 which constitutes the fluid inlet opening to the casing 1.

55. A core 10 is mounted for rotation in the chamber 2 and said core is provided with a centrally disposed inner chamber 11 having communication with the inlet opening 9 through an internally threaded annulus 12 mounted in said core for rotation therein, as clearly seen in Fig. 3 of the drawings. The annulus 13 has its inner periphery threaded to receive a conduit (not shown) which is threaded through the inlet opening 9 for conveying the fluid into the chamber 11 of 60 the valve. It will thus be seen that the annulus 12 is mounted on the inner end of the fluid supply conduit and the core 10 rotatably encircles said annulus. A packing ring 13 is 65 mounted in the outer periphery of the annulus 12 for engagement with the core 10 in a manner to seal the joint therebetween. The chamber 11 is provided with a passage 14 extending from one side thereof which is 70 adapted to be selectively brought into communication with the ports 4 and 5 when the core 10 is rotated in the casing. The core 10 is further provided with a circumferentially 75 extending groove or channel 15 the intermediate portion of which is at all times in communication with the outlet opening 3 and the opposite ends of which are adapted to be selectively brought into registry with the ports 4 and 5. As will be seen in Figure 2 80 of the drawings, when the passage 14 of the inner chamber 11 of the core 10 is in engagement with one of the ports 4 and 5, one end of the channel 15 is in communication with the other of said ports.

85. The casing 1 is provided, on its forward side, with a circular opening 16 for rotatably receiving the annular inner portion 17 of a polygonal shank 18 which terminates in a reduced, circular threaded end portion 19 upon which is threaded a retaining nut 20 90 95 100

adapted to secure an actuating handle 21 on said polygonal shaft 18. A thrust washer 22 is disposed between the core 10 and the front wall of the casing 1. If desired, a thrust bearing in the form of anti-friction balls or rollers may be disposed between the core 10 and the front wall of the casing 1 in lieu of the washer 22.

In use, with the core in the position illustrated in Figure 2 of the drawings, fluid enters the chamber 11 through the passage 9 and the annulus 12 and flows from said chamber through the passage 14 and through the port 5 to the cylinder in which the piston to be actuated is disposed through the pipe 23. The fluid returns through the pipe 24 from the cylinder, enters the port 4 and passes into the channel 15 which is now in communication with said port 4 and from said channel 15 the fluid passes out through the outlet opening 3. Should the core 10 be rotated in a manner to bring the passage 14 into communication with the port 4 and the channel 15 into communication with the port 5, the flow of the fluid to the cylinder and through the valve will be reversed, as will be apparent. By shifting the core 10 so that the free end of the partition 6 extends over and closes the end of the passage 14, the valve will be in closed position and the fluid will be prevented from flowing therethrough in either direction.

It is believed that the many advantages of a fluid reversing valve constructed in accordance with this invention will be readily understood, and although the preferred embodiment of the invention is as illustrated and described, it is to be understood that changes in the details of construction may be had which will fall within the scope of the invention as claimed.

What is claimed is:—

1. A fluid reversing valve of the character described comprising a casing having a circular chamber therein provided with a pair of ports on one side and an outlet port spaced from said pair of ports, said casing being further provided with a centrally disposed inlet port, and a core mounted for rotation in the chamber having an inner chamber constantly in communication with the inlet port of the casing and a circumferentially extending peripheral channel constantly in communication with the outlet port of the casing, said channel adapted to be selectively brought into communication with the first named ports, said inner core chamber having an outlet passage for selective communication with the first named ports whereby communication between the inlet port and one of the first named ports and between the outlet port and the other of said first named ports is simultaneously established upon rotation of the core in the casing.

2. A fluid reversing valve of the character

described comprising a casing having a circular chamber therein provided with a pair of ports on one side of the casing, a partition extending between the ports, said casing being further provided with an outlet port spaced from the pair of ports and a centrally disposed inlet port, and a rotary core mounted in the chamber having an inner chamber constantly in communication with the inlet port and a circumferentially extending peripheral channel constantly in communication, at an intermediate portion, with the outlet port and adapted to have its opposite end portions selectively brought into communication with the first named ports of the casing chamber, the inner core chamber being provided with an outlet passage adapted to be selectively brought into communication with the first named ports whereby communication between the inlet port and one of the first named ports and between the outlet port and the other of said first named ports is simultaneously established upon rotation of the core in the casing, the outlet port of the inner chamber of the core being further adapted for disposition in opposed relation to the free end of the partition in a manner to be closed thereby.

In testimony whereof I affix my signature.

WILHELM FRIEDRICH HOHULIN.
